US00D962780S

(12) **United States Design Patent** (10) Patent No.: **US D962,780 S**
(45) Date of Patent: **** Sep. 6, 2022**

(54) **DISPENSER**

- (71) Applicant: **S. C. JOHNSON & SON, INC.**,
Racine, WI (US)
- (72) Inventor: **Brian Davis**, Burlington, WI (US)
- (73) Assignee: **S. C. Johnson and Son, Inc.**, Racine,
WI (US)

(**) Term: **15 Years**

(21) Appl. No.: **29/818,216**

(22) Filed: **Dec. 7, 2021**

Related U.S. Application Data

(63) Continuation of application No. 29/798,308, filed on Jul. 7, 2021, now Pat. No. Des. 940,564, which is a continuation of application No. 29/710,486, filed on Oct. 23, 2019, now Pat. No. Des. 927,314.
